(57) **CLAIM**

The ornamental design for a removable chuck, as shown and described.

DESCRIPTION

FIG. 1 is a front perspective view of a removable chuck; FIG. 2 is a front view of the removable of FIG. 1; FIG. 3 is a rear view of the removable chuck of FIG. 1; FIG. 4 is a right side view of the removable chuck of FIG. 1; FIG. 5 is a left side view of the removable chuck of FIG. 1; FIG. 6 is a top view of the removable chuck of FIG. 1; and, FIG. 7 is a bottom view of the removable chuck of FIG. 1. The broken line showing in dash-dot form is provided for the purpose of indicating the boundaries of the claimed design. All the broken lines shown in the drawings illustrate portions of the removable chuck that forms no part of the claimed design.
